[57] CLAIM

The ornamental design for a hanging light fixture, as shown and described.

DESCRIPTION

FIG. 1 is a perspective view of a hanging light fixture showing my new design having three lights;

FIG. 2 is a side elevational view thereof, all sides being identical;

FIG. 3 is a top plan view thereof;

FIG. 4 is a bottom plan view thereof;

FIG. 5 is a perspective view of an alternative embodiment having five lights;

FIG. 6 is a side elevational view thereof, all sides being identical;

FIG. 7 is a top plan view thereof;

FIG. 8 is a bottom plan view thereof;

FIG. 9 is a perspective view of a second alternative embodiment having seven lights;

FIG. 10 is a side elevational view thereof, all sides being identical;

FIG. 11 is a top plan view thereof; and,

FIG. 12 is a bottom plan view thereof.
